UNITED STATES PATENT OFFICE

WALDEMAR A. ENDTER, OF LONG BEACH, CALIFORNIA

DOORLOCK

Application filed September 13, 1930. Serial No. 481,707.

This invention relates to a door lock for the doors of houses, automobiles, and the like, and the prime object of my invention is to provide a lock which will hold the door tightly against the stop at all times, and thereby prevent rattling of the door.

Another object is to provide a locking bolt of the character stated which can be applied to many well-known types of locks now in use.

A further object is to provide a lock which is simple in construction and effective in use.

Further advantages of my invention reside in the fact that the door stop need not be set accurately relative to the door, but the door will be held tightly against it irrespective of slight errors in construction. Also my locking bolt will operate with equal effectiveness if the door shrinks away from the jamb.

Other objects, advantages, and features of invention may appear from the accompanying drawing, the subjoined detailed description, and the appended claims.

In the drawing

Figure 1 is a transverse, sectional view of my lock in position in a door.

Figure 2 is a diagrammatic plan view of the locking bolt and strike plate.

Figure 3 is an end view of the sliding wedge dog.

Referring more particularly to the drawing, the numeral 1 indicates a door, and 2, the usual jamb to which a stop 3 is attached. My lock 4 is mounted in the door 1 and includes a metal sheath or casing 5 which fits into a suitable bore or other recess in the door. A multi-headed locking bolt 6 is rotatably mounted in the door 1 adjacent the outer swinging edge thereof. This bolt is preferably formed with four teeth or heads, and its function is to hold the door tightly against the stop, as will be further described.

The locking bolt does not move horizontally, but merely rotates on its axis 7, which axis is mounted in the metal sheath.

A sliding dog 8 is provided with long guides 9—9 so that it will move back and forth horizontally without binding. The

outer end of this dog is tapered, as shown at 10, and engages one of the teeth or heads of the locking bolt 6, as shown in Figure 1.

A strike plate 11 is mounted in the jamb 2 and preferably provided with a central wall 12 against which one of the teeth of the locking bolt bears to hold the door tightly against the jamb. As shown in Figure 1, the tip of one of the teeth of the locking bolt rests against the tapered surface 10 and consequently the sliding dog 8 can be moved outwardly, thus tending to further rotate the locking bolt 6, and will therefore hold the door tightly against the stop 3. The tapered face 10 is not so abrupt but that the locking bolt cannot slip thereon. Consequently once the door is held against the stop, it will be held there until the door is opened. The sliding dog 8 is yieldably pressed towards the locking bolt 6 at all times by a coil spring 13 which encircles a retracting pin 14 which extends rearwardly from the dog 8. The head of the pin 14 is engaged by a yoke 15 which yoke is reciprocated by a cam on the door knob post 16. This construction is usual and well-known in the art.

If the door should shrink, a situation might arise that the locking bolt 6 would not be rotated a sufficient amount so that one of the heads thereof would rest on the tapered surface 10. Therefore, to positively insure the proper positioning of the locking bolt at all times, I provide an inwardly yieldable fin 17 on the center wall 12 of the strike plate. This fin is normally urged outwardly by a spring 18 of any well-known type.

As shown in Figure 2, as the door closes, one of the heads of the locking bolt 6 will depress the fin 17 and the spring 18 will then urge the fin outwardly and rotate the locking bolt to a position where another of the arms will bear against the tapered surface 10. Thus there is a positive assurance that the locking bolt will always be moved to a position so that the sliding dog 8 can co-act therewith and thus effectively hold the door against rattling.

Having described my invention, I claim:

1. In combination with a door and a jamb therefor, a stop on the jamb and a strike plate in the jamb, a lock including a multi-headed locking bolt, means rotatably mounting the bolt adjacent the outer edge of the door, one of the heads of the locking bolt engaging the strike plate, a wedge-shaped dog slidably mounted in the door, said last named dog engaging another of the heads of the locking bolt, and spring means engaging the sliding dog whereby said sliding dog is yieldably pressed towards the locking bolt, thereby tending to rotate said locking bolt and to hold the door against the stop, means to retract said sliding dog, a wall in said strike plate against which one of the heads of the locking bolt bears, a fin pivotally mounted to said wall, and spring means urging said fin outwardly.
2. In a latch construction, a rotary bolt capable of free rotation in all positions when released, including a plurality of heads, any one of which is adapted to engage a keeper, means engageable with any one of the heads, said means including means for imposing a continuous rotation of the bolt in a latching direction when the bolt is in keeper engaging position.
3. In a latch construction, a casing, a rotary bolt mounted in the casing, said bolt being capable of free rotation in all positions when released, including a plurality of heads any one of which is adapted to engage a keeper, a movable dog arranged in the casing and engageable with any one of the heads, said dog having a tapered face cooperating with one of the heads for imposing a continued rotation of the bolt in a latching direction when the bolt is in keeper engaging position.
4. In a latch construction, a casing, a rotary bolt mounted therein, said bolt being capable of free rotation in all positions when released, and including a plurality of heads any one of which is adapted to engage a keeper, a sliding spring projected dog arranged in the casing, guide means for the dog, said dog being engageable with any one of the heads, the dog having a tapered face cooperating with one of the heads for imposing a continued rotation of the bolt in a latching direction when the bolt is in keeper engaging position, and means for retracting the sliding dog whereby the bolt is free to rotate.
5. In a latch construction, a rotary bolt capable of free rotation in all positions when released, including a plurality of heads any one of which is adapted to engage a keeper, a dogging mechanism adapted to engage successive heads of the bolt in non-latching position, said dogging mechanism including means for imposing a continued rotation of the bolt in a latching direction when one of the heads is in keeper engaging position.
6. In a latch construction, a rotary bolt capable of free rotation in all positions when released, including a plurality of heads, any one of which is adapted to engage a keeper, a sliding dog adapted to engage successive heads of the bolt in non-latching position, means for normally projecting the dog whereby upon rotation of the bolt in a latching direction said dog is automatically retracted by one of the successive heads, and upon disengagement of said successive head from the dog, permits the dog to assume a dogging position relative to said successive head, and means on the dog cooperating with said successive head to impose a continued rotation of the bolt in a latching direction.

In testimony whereof, I affix my signature.
